CLAIM

The ornamental design for a cover of a comic book case, as shown and described.

DESCRIPTION

FIG. 1 is a perspective view of an outside of a cover of a comic book case from an upper left side.

FIG. 2 is a perspective view of an inside of the cover from a lower left side.

FIG. 3 is an elevation view of the top side of the cover, the bottom side elevation view being a mirror image of that shown.

FIG. 4 is an elevation view of the right side of the cover, the left side elevation view being a mirror image of that shown.

FIG. 5 is a plan view of the inside of the cover.

FIG. 6 is a plan view of the outside of the cover.

FIG. 7 is a perspective view of the inside of the cover from an upper left side and a comic book shown in broken lines unclaimed, resting on the inside of the cover.

FIG. 8 is an exploded perspective view the case showing the outside of the cover and a base shown in broken lines, unclaimed.

FIG. 9 is an exploded perspective view the case showing the inside of the cover and the base shown in broken lines, unclaimed.

FIG. 10 is an exploded elevation view of the case including the cover and the unclaimed base from a top side, the bottom side exploded elevation view being a mirror image of that shown.

FIG. 11 is an exploded elevation view of the case including the cover and the unclaimed base from a right side, the left side exploded elevation view being a mirror image of that shown.

(Continued)

FIG. 12 is an exploded plan view of the inside of the cover adjacent the outside of the unclaimed base.

FIG. 13 is an exploded plan view of the outside of the cover adjacent the inside of the unclaimed base; and,

FIG. 14 is an exploded perspective view the case showing the inside of the cover as well as the outside of the base and a book shown in broken lines unclaimed, resting on the inside of the cover.

The base shown in FIGS. 8, 9, 10, 11, 12, 13 and 14, which is assembled together with the cover to form the case, is shown in broken lines and forms no part of the claimed design. The book shown resting on the cover in FIG. 7 and on the cover in FIG. 14 is shown in broken lines and forms no part of the claimed design. The four small post receptacles shown just inside the four corners of the inside of the cover in FIGS. 1, 2, 3, 4, 5, 7, 8, 9, 10, 11, 12 and 14 are shown in broken lines and form no part of the claimed design.

1 Claim, 12 Drawing Sheets
